CLAIM

The ornamental design for a phone case, as shown and described.

DESCRIPTION

FIG. 1 is a front, right side perspective view of a phone case showing my new design, shown in a fully open state;

FIG. 2 is a back, left side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a second back, left side perspective view thereof shown in a fully open state, with the rear wallet portion shown extended;

FIG. 10 is a second front, right side perspective view thereof shown in a fully open state, with the rear wallet portion shown extended;

FIG. 11 is a front, right side perspective view thereof of a partially closed state of the phone case;

FIG. 12 is a front, right side perspective view thereof of the phone case shown in a fully closed state; and,

FIG. 13 is an enlarged view of the selected portion 13 in FIG. 1.

The broken lines, and unshaded regions surrounded by broken lines, showing features of the article in the drawings depict portions of the phone case that form no part of the claimed design. The broken line circles in FIGS. 1 and 13 are included for the purpose of describing the partial enlarged view and form no part of the claimed design.
